LAST CONSTRUCTION

Anthony Mascioli, New York, N. Y.

Application June 3, 1955, Serial No. 513,067

3 Claims. (Cl. 12—133)

The present invention is directed to novel and useful improvements in a last construction and is a continuation-in-part of my copending application Serial No. 456,908, filed September 20, 1954, abandoned in favor of this application.

The primary object of the invention is to provide a last construction whereby a shoe produced from the last construction will provide ample lateral clearance across the ball of a foot received in the shoe as well as ample longitudinal clearance of the toe portion of a foot received in the shoe, which last is yet so constructed that a foot received in a shoe made therefrom will be firmly gripped to prevent both lateral and longitudinal sliding of the foot received in the shoe.

It is a further object of the invention, in conjunction with the primary object, to provide a shoe last having a novel foreshortened toe portion acting in conjunction with a deep concavity along the inner longitudinal edge of the shank portion of the last whereby a shoe made from the last will firmly grip the arch of a foot received therein to thereby prevent lateral or longitudinal shifting of the foot within the shoe and effectively prevent both inner and outer pronation of the foot while in addition preventing a loose fit of the foot in the heel portion of the shoe.

A further object of the invention is in the provision of a last construction particularly adapted for the making of ladies' high heeled shoes wherein the last is provided with a foreshortened toe portion and an extended shank portion as compared to a usual last of the same size and width whereby the angle of incidence of the shank portion relative to the heel portion of the last will be less than that of the usual last.

These together will other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side elevational view showing an embodiment of my last construction in accordance with the invention with a usual last of the same size and width being shown in dotted outline;

Figure 2 is a bottom plan view of Figure 1;

Figure 3 is an elevational view taken from the outer side of the last of Figure 1; and

Figure 4 is a vertical transverse sectional view taken through the waist portion of the last substantially along the plane indicated by section line 4—4 of Figure 1, showing the reduced cross-sectional area of my improved last relative to the usual last shown in dotted outline adjacent the waist line of the lasts.

In the construction illustrated in the drawing, the last is provided with a toe portion 10, ball portion 12, shank portion 14 and heel portion 16. As suggested in Figures 1 and 3, the ball and toe portions of the last have a substantially flat, or very slightly convexed, bottom surface

2

18 while the heel portion has also a substantially flat, or very slightly convexed, bottom surface 20.

The bottom surfaces of the heel portion 16 and the toe and ball portions 10 and 12 are sharply inclined 5 relative to one another, being spaced from one another by the connecting shank portion 14. The shank portion merges smoothly into the heel portion of the shoe so there is no visible break in the line of the shank at the breast line, indicated by the numeral 15 in Figure 2 of 10 the last.

The toe and ball portions 10 and 12 of the last are considerably foreshortened over the comparable portions of a usual last of the same size and width as shown in Figure 1. Further, the shank is consequently extended 15 in length over the comparable shank length of the usual last so that the angle of incidence between the heel portion 16 of the last and the ball and toe portions 12 and 10 of the last of my invention is greatly reduced from the comparable angle of incidence of the usual last as will be indicated from the lines 26 and 32 leading from a point of tangency to the heel portion 16 of the last to points of tangency with the ball portion respectively of my improved last and the ball portion of a usual last of the same size. As will be noted from a comparison of the 20 arrowed lines 28 and 34 respectively, the angle of incidence of line 26 is less than that of line 32.

By comparison, the line 32 is tangent to the heel and ball portions of a conventional last and makes an angle of incidence with the line 30 representing a base line of 30 about 41°. The line 26 tangent to the heel and ball portions of my improved last makes an angle of incidence of approximately 38° with respect to the base or reference line 30 with the heel of the usual last and my improved last at the same vertical elevation above the base line 30.

35 Further, the last has a deep cavity 36 along the inner longitudinal edge of the shank portion thereof which extends from the break line 40 of the last to a position in front of the breast line 15 of the last. Thus, a reduced cross-sectional area is provided in the shank portion of the last as compared to the usual last as will be noted in the dotted line comparison of Figure 4 taken on a section approximately across the waist of the last. Further, this concavity causes the mass of the last to be disposed toward the outer longitudinal edge thereof in my improved 40 last construction.

45 With this construction, the foreshortened toe portion cooperates with the concavity along the inner longitudinal edge of the last to cause a foot received in a shoe made from the last to be disposed forward in the shoe and retained against any longitudinal slippage in the shoe during walking. Yet, the mass of the last being disposed 50 toward the outer longitudinal edge of the last from the center line 42 of the last in my improved last construction permits lateral flexure of the foot and particularly to the ball portion of a foot received in a shoe made from the last during walking.

55 To prevent lateral slippage of the foot received in a shoe made from my improved last construction, the last has along the break line thereof a slightly concave recess 60 of ellipsoidal shape as designated by the numeral 44 particularly noted in Figure 2.

65 The major axis 45 of the ellipsoidal recess is disposed generally parallel to the break line 40 and displaced therefrom toward the inner longitudinal edge of the last and forwardly of the break line whereby the major portion of the recess will be located in the ball portion of the last. The minor axis of the ellipsoidal recess extends generally in the direction of the longitudinal center line 42 of the last.

70 The recess 44 is disposed intermediate the edges of the last and provides a transverse arch support for the middle metatarsals and serves in conjunction with the concavity 36

in the shank portion of the last to lock the foot against lateral displacement when received in a shoe made from the last whereby the foot will be locked both against lateral slippage and longitudinal slippage by virtue of the relation of the ellipsoidal recess 44 to the shank portion concavity 36.

With this construction, a foreshortened toe portion as noted previously may be utilized while still affording ample lateral and longitudinal clearance for a foot in a shoe made from the last. The recess 44 causes a corresponding bulge in a shoe made therefrom along with a corresponding shank bulge from concavity 36 in a shoe made therefrom providing for smooth natural walking action with the transition of the weight of the foot from the scaphoid to the cuboid stream in an easy and natural manner without inward or outward pronation of the foot or without longitudinal or lateral rubbing of the foot due to displacement thereof in the shoe.

Further the break line 40 of the last is sharply inclined to follow the natural laterally offset relation of the metatarsals of the foot to one another in a shoe made from the last. This inclination will be readily apparent from an examination of Figure 2 wherein it will be noted that the distance from the heel extremity 46 of the longitudinal center line 42 of the last to the point 48 on the inner longitudinal edge of the break line is considerably greater than the distance from the point 46 to the point 52 at the outer longitudinal edge of the break line 40.

The change in configuration of my improved last construction as compared to that of a usual last of the same size and width, while giving my improved last a shorter and lower appearance is accomplished without any difference in cubic volume between the two lasts, and without any difference in heel height of shoes made from the two lasts.

From the foregoing description, the last construction of the present invention will be readily apparent to those skilled in the art and the beneficial effects therefrom will also be readily apparent. Accordingly, further description is believed unnecessary and what is claimed as new is as follows.

What is claimed as new is as follows:

1. A shoe last having a foreshortened toe portion and an extended shank portion extending to the heel portion thereof as compared to a usual last of the same size and width whereby the angle of incidence of the shank portion relative to the heel portion of the last will be less than that of the usual last, said last having a sharply inclined relatively straight break line, said last having a deep concavity along the inner longitudinal edge of the shank portion extending from the break line to a position in front of the breast line whereby a reduced cross-sectional area is provided in the shank portion as compared to a usual last and the mass of the last is disposed toward the outer longitudinal edge of the last, said foreshortened toe portion and said concavity causing a foot received in a shoe made from the last to be disposed forward in the shoe, said last having the same cubic volume as the usual last of the same size and width.
2. The combination of claim 1 wherein said last is provided with an ellipsoidal recess along the break line intermediate the outer and inner longitudinal edges of the last thereby providing a transverse arch support in a shoe made from the last to lessen pronation of a foot received in the shoe and to prevent lateral shifting of a foot within the shoe.
3. The combination of claim 2 wherein the major axis of the ellipsoidal recess is disposed generally parallel to the break line.
